POST ANCHORED DOOR LATCH.

Filed July 18, 1928

UNITED STATES PATENT OFFICE

WALTER E. SCHLAGE, OF SAN FRANCISCO, CALIFORNIA, ASSIGNOR TO SCHLAGE LOCK COMPANY, OF SAN FRANCISCO, CALIFORNIA, A CORPORATION OF CALIFORNIA

POST ANCHORED DOOR LATCH

Application filed July 18, 1928. Serial No. 293,581.

This invention relates to door latches, such as shown in my co-pending application entitled "Door latch" filed April 18, 1928, Serial 270,815, and especially to improvements whereby the interlock between the latch unit and the latch actuating unit is simplified and rendered more rigid.

The object of the present invention is to generally improve and simplify the construction and operation of door latches of the character described, and especially to provide an interlock between the latch actuating unit and the latch unit whereby they will be rigidly connected when assembled in a door, and whereby proper co-relation between the movable operating parts of the mechanism will be maintained, and binding action entirely eliminated.

The door latch is shown by way of illustration in the accompanying drawings, in which:

Fig. 1 is a horizontal longitudinal section taken on line I—I of Fig. 2, said view showing the door latch assembled in the door, 25 Fig. 2 is a vertical longitudinal section taken on line II—II of Fig. 1,

Fig. 3 is a perspective view of the inner end of the inside spindle,

Fig. 4 is a perspective view of the inner 30 end of the outside spindle,

Fig. 5 is a perspective view of the retractor,

Fig. 6 is a side elevation of the inner end of the latch housing.

Referring to the drawings in detail, and particularly to Figs. 1 and 2, A indicates a portion of a door in which the door latch is assembled and inserted. To receive the latch, two holes are drilled in the door, one through the edge, as indicated at B, to receive the latch housing, and one at right angles thereto, as indicated at C, to receive the escutcheon plates and the latch actuating mechanism. The latch mechanism comprises a housing, generally indicated at D, which consists of 40 top and bottom plates 2 and 3, an end plate 4, and side plates 5 and 6. The inner end of the latch housing is closed by the end plate 4, but the side plates are each provided with three holes, such as indicated at 7, 8 and 9, 45 to permit the spindles to pass therethrough,

and also a pair of anchor posts, as will hereinafter be described.

Slidably mounted in the housing is a retractor, generally indicated at E, see Figs. 2 and 5, and connected therewith is the bolt or latch proper, as indicated at F. The retractor may be constructed in any suitable manner. In this instance it is shown as formed from a piece of strap iron, which is bent to a rectangular shape so as to form top and bottom sections, indicated at 10 and 11 respectively, and end sections 12 and 14. The retractor is guided by the top and bottom plates 2 and 3, and by the side plates 5 and 6, as the width of the retractor is equal to the spacing between the side plates and the height is equal to the distance between the top and bottom plates of the housing.

The forward end of the retractor is provided with an opening 15. A bolt 16, suitably secured to the latch F, extends through this opening and it is secured to the retractor by means of a collar 17, and a head member 18. A bar 19 extends cross-wise of the housing and this bar is also perforated to permit the bolt 16 to pass therethrough. A spring 20 surrounds the bolt 16, and is interposed between the latch F and the cross bar 19, and as such exerts a pressure which normally maintains the retractor and the latch in the extended position shown in Figs. 1 and 2.

The latch actuating unit illustrated in the present instance consists of an outer escutcheon plate 22, and an inner escutcheon plate 23. These plates engage the opposite face of the door, and they are secured thereto by a pair of posts 24 and 25, and a pair of cooperating screws 24a and 25a, which extend through the inner escutcheon plate. The posts 24 and 25 are formed integral with the outer escutcheon plate 22, or otherwise secured thereto, and their outer ends extend into perforated guide lugs 26 formed on the inner face of the escutcheon plate 23 so as to maintain a coaxial alignment between the escutcheon plates and the mechanism to be supported thereby. Each escutcheon plate is also provided with a central hub member, such as shown at 27 and 28, and these hub 50

members form journal members for a pair of spindles, indicated at 30 and 31. Both spindles are provided with knobs, such as shown at 30a and 31a, and these knobs serve the function of transmitting rotary movement to the spindles when the door latch F is to be retracted or projected.

The spindles are constructed as shown in Figs. 1, 3 and 4. These spindles telescope, one with relation to the other, the largest diameter spindle 30 carrying the outer knob 30a and the smaller diameter spindle 31 carrying the inner knob 31a. In fact, the outer spindle 30 is extended into the bearing hub 27 of the inner escutcheon plate and as such rotates not only with relation to the bearing hub 27 but also with relation to the outer bearing hub 28. The inner spindle 31 in turn rotates within the outer spindle. Both spindles are cut away, as indicated at 32 and 33. A connecting web is left, as indicated at 34 and 35 and these webs form the function of roll back members, as they engage the inner end 12 of the retractor and as such impart a reciprocal movement thereto when one spindle or the other is rotated. The cut away portions indicated at 32 and 33 perform another function besides that of forming the roll back members 34 and 35—that is to wit—that of securing the spindles against endwise movement either in an inward or outward direction. This is due to the fact that the cut away portions straddle the end plate 12 of the retractor and as the retractor is held against lateral movement by means of the side plates 5 and 6 of the latch housing it is obvious that the spindles are secured against endwise movement in either direction.

In actual operation when the door is prepared for the reception of the door latch by drilling the holes indicated at B and C, it is first necessary to insert the latch housing D, secondly, when this is inserted, the outer escutcheon plate is applied to the door by inserting the posts 24 and 25 through the perforations 8 and 9 formed in the side plates 5 and 6 of the latch housing; third, applying the inner escutcheon plate 23 and securing it by means of the screws 24a and 25a; fourth, depressing the latch F or pushing it inwardly until the end plate 12 clears the opening 7, or until the end plate assumes the dotted line position shown at 12a, Fig. 6, fifth, inserting the outer spindle, and sixth, inserting the inner spindle.

It is then only necessary to release the latch so as to permit the retractor to move forwardly to the full line position shown in Figs. 2 and 6. This forward movement causes the end plate 12 of the retractor to move inwardly, between the cut away portions 32 and 33 of the spindles, thus securing them against endwise removal. The knobs may then be applied if this has not already been done,

and the installation of the door latch is complete.

It is old to provide a latch housing such as here illustrated through which a spindle is passed, as through openings 7, to form an interlock between the latch housing and the spindle. Such an assembly, however, has proven impractical, as it has been difficult to maintain the right angular position between the spindle and the housing, and due to this difficulty, binding action would take place between the movable parts of the mechanism. In the present instance this difficulty has been entirely overcome by providing the anchor posts indicated at 24 and 25. These, together with the spindles form a three point interlock between the latch actuating unit and the latch housing, and between the co-operating movable parts of the mechanism in both units. This three point interlock insures coaxial alignment of the escutcheon plates and the telescoping spindles so that no binding action can take place between the spindles proper nor between the spindles and the bearing hubs 27 and 28. Nor can any binding action take place between the retractor and the spindles as the latch housing is maintained at right angles to the spindles due to the three point interlock obtained by the anchor posts and the spindle proper.

Perfect co-relation and operation of the mechanism is thus maintained and a rigid structure is provided, and an exceedingly simple structure and mechanism is insured.

While certain features of the present invention are more or less specifically described, I wish it understood that various changes may be resorted to within the scope of the appended claims similarly that the materials and finishes of the several parts employed may be such as the manufacturer may decide, or varying conditions or uses may demand.

Having thus described my invention, what I claim and desire to secure by Letters Patent is:

1. In a door latch of the character described a latch housing, a pair of escutcheon plates one on each side thereof, a spindle journaled in the escutcheon plates and extending through the housing and at right angles thereto, a post extending through the housing and secured at one end to one escutcheon plate, a guide member on the opposite escutcheon plate receiving the other end of the post, and means whereby the post is secured to the guide member.

2. In a door latch of the character described, a latch housing, a pair of escutcheon plates one on each side thereof, a spindle journaled in the escutcheon plates and extending through the housing and at right angles thereto, and a pair of posts extending through the housing, and secured at one end to one escutcheon plate, guide members on the opposite plate to receive the other ends

of the posts, and means whereby the posts are secured to the guide members.

3. In a door latch of the character described a latch housing, a pair of escutcheon plates one on each side thereof, a spindle journaled in each escutcheon plate and extending into the housing and at right angles thereto, a pair of posts extending through the housing and secured at one end to one escutcheon plate, guide members on the opposite escutcheon plate to receive the other ends of the posts and means whereby the posts are secured to the guide members.
